US00D926739S

(12) **United States Design Patent** (10) **Patent No.:** **US D926,739 S**
(45) **Date of Patent:** **** Aug. 3, 2021**

(54) **CASE FOR AN ELECTRONIC DEVICE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/655,330**

(22) Filed: **Jul. 2, 2018**

(51) LOC (13) Cl. **14-03**

(52) U.S. Cl.
USPC **D14/250; D13/103**

(74) *Attorney, Agent, or Firm* — Sterne, Kessler, Goldstein & Fox PLLC.

(57) **CLAIM**

The ornamental design for a case for an electronic device, as shown.

DESCRIPTION

FIG. 1 is a bottom front perspective view of a case for an electronic device showing the claimed design;
FIG. 2 is a top front perspective view thereof;
FIG. 3 is a bottom rear perspective view thereof;
FIG. 4 is a top rear perspective view thereof;
FIG. 5 is a front view thereof;
FIG. 6 is a rear view thereof;
FIG. 7 is a left side view thereof;
FIG. 8 is a right side view thereof;
FIG. 9 is a top view thereof; and,
FIG. 10 is a bottom view thereof.

1 Claim, 8 Drawing Sheets
